UNITED STATES PATENT OFFICE

158,980

LIGHTING FIXTURE DISPLAY STAND

Herbert S. Leebaw, Youngstown, Ohio

Application December 9, 1948, Serial No. 150,051

Term of patent 3½ years

(Cl. D80—9)

To all whom it may concern:

Be it known that I, Herbert S. Leebaw, a citizen of the United States, residing at Youngstown, in the county of Mahoning and State of Ohio, have invented a new, original, and ornamental Design for a Lighting Fixture Display Stand, of which the following is a specification, reference being had to the accompanying drawing, forming a part thereof.

The figure is a perspective view of the lighting fixture display stand, showing my new design.

I claim:

The ornamental design for a lighting fixture display stand, as shown.

HERBERT S. LEEBAW.
